UNITED STATES PATENT OFFICE.

WALTER J. PAINE, OF BOSTON, MASSACHUSETTS.

ELECTRICALLY-CONTROLLED ELEVATOR.

SPECIFICATION forming part of Letters Patent No. 422,968, dated March 11, 1890.

Application filed June 5, 1889. Serial No. 313,121. (No model.)

To all whom it may concern:

Be it known that I, WALTER J. PAINE, of Boston, county of Suffolk, State of Massachusetts, have invented an Improvement in Electrically-Controlled Elevators, of which the following description, in connection with the accompanying drawings, is a specification, like letters and figures on the drawings representing like parts.

- 10 This invention relates to a novel system for electrically controlling the movement or travel of a car or carriage from one point or station to another or distant point or station, and has for its object to provide suitable mechanism, 15 as will be described, whereby the movement of the car or carriage may be automatically controlled from any one of a series of stations or stopping-points, and also, if so desired, from the car itself.
- 20 My invention is especially adapted, among other things, to be applied on elevators of any usual or well-known construction, such as now commonly in use; and, in order that my invention may be readily comprehended, I shall specifically describe its operation when applied 25 to an elevator.

In accordance with my invention the motor mechanism employed to raise the elevator-car, which mechanism may be of any usual 30 construction, is governed, as herein shown, by two electro-magnets in an electric circuit extended through the elevator-car and provided with a manual switch carried by the car to be operated by a person on the car, and 35 with an automatically-operated switch also carried by the car and which is operated outside the car at a predetermined point.

The operation of the automatically-operated switch may be controlled, as will be described, 40 either from within or on the car, and also from a given station or point outside the said car—as, for instance, at a floor of the building in which the elevator is located. At each station or floor of the building is located a switch 45 provided, as herein shown, with two contact-points, one of which co-operates with a terminal of a circuit connected to the electro-magnets controlling the motor mechanism, the other terminal being in circuit with an auxiliary magnet controlling a cam which, when 50 in position, as will be described, actuates the automatically-operated switch on the car to

break the main line or circuit and stop the movement or travel of the car at that station or landing.

55 The circuit of the motor-operating magnets connected to the switch at the station or floor referred to has located in it a movable circuit-controller operated, as will be described, by a cam or projection carried by the car to control the circuit of one or the other of the main-line magnets, so that when the switch at the floor or station is closed the circuit of that one of the main-line magnets is closed which will operate the motor mechanism to send the 60 elevator-car to the station or floor at which the said switch was closed.

65 The circuit of one of the main-line magnets is momentarily closed when the switch at the floor or station or on the car is closed, and the 70 continuity of the magnet-circuits to operate the motor is maintained, as will be described, even after the switch at the floor or station is opened, the said main-line circuit being maintained closed until positively opened 75 either by a manual switch or by the automatically-operated switch carried by the car.

80 My invention therefore consists, essentially, in the combination, with a car or carriage and a motor mechanism to cause the said car or carriage to travel, of a magnetic device operatively connected to the car or carriage to control the operation of the motor mechanism from the car, a manual switch and an independent automatic switch carried by the car 85 in circuit with the magnetic device, and a cam or projection in the path of movement of the car to operate the said automatic switch and stop the car, substantially as will be described.

90 Other features of my invention will be pointed out in the claims at the end of this specification.

Figure 1 is a diagram representing a sufficient portion of an elevator, one form of operating mechanism therefor, and the electrical devices for controlling the operating mechanism in accordance with my invention. Fig. 2 is a top or plan view, partially broken out, of a sufficient portion of the motor mechanism and the electrical device controlling it to enable my invention to be understood. Fig. 3 is a section of the motor mechanism shown in Fig. 2 on line x x looking toward

the right; Fig. 4, a side view of a part of the motor mechanism and its operating-magnets shown in Fig. 2; Fig. 5, a detail of one form of operating-magnet. Fig. 6 is a sectional de-
 5 tail showing the bottom of the elevator-car and a portion of the side wall of the elevator-well; Fig. 7, a detail showing the bottom of the elevator-car and a portion of the elevator-door; Fig. 8, a modified form of the selecting device carried by the car; Fig. 9, a rear side view of the device shown in Fig. 8; Fig. 10, a detail representing successive floors of the elevator-well; Figs. 11, 12, and 13, details to be referred to; Fig. 14, an enlarged detail of
 15 the selecting device carried by the car; Fig. 15, a rear elevation of the selecting device shown in Fig. 14; Fig. 16, a front elevation of the device situated at each landing for controlling the elevator at the landing; Fig. 17,
 20 a section of the device shown in Fig. 16 on line $x' x'$; Fig. 18, a section of the device shown in Fig. 16 on line $y' y'$; Fig. 19, a diagram of a modification to be referred to; Fig.
 25 19^a, a section on line $y' y'$; Fig. 19; and Figs. 20 to 22, inclusive, modifications embodying the principle of my invention to be referred to.

The elevator-car A, herein represented as a passenger-car provided with the usual door 30 A', is suspended in an elevator-well A² by preferably metallic or wire cables a a' a², the cables a a' being passed about suitable sheaves at the top of the building and connected to counterbalancing-weights a³, and 35 the cable a² being passed about the sheaves at the top of the building and connected to a drum a⁴, all substantially as with elevators as now commonly constructed.

The elevator-car A is raised by a motor 40 mechanism, herein shown, of that class known as the "belt system," consisting of a straight belt a⁵, passed about a pulley a⁶ (see Fig. 2) on a driving-shaft a⁷ and about a similar pulley on the shaft a⁸ of the drum a⁴, and of 45 a cross-belt a⁹ on a pulley a¹⁰ on a shaft a^x, in line with the shaft a⁷, the said cross-belt being passed about a pulley a¹² on the shaft a⁸, opposite to the pulley about which the belt a⁵ is passed. The shaft a⁷ is provided with a 50 fast pulley a¹³ and a loose pulley a¹¹, and the shaft a^x is provided with a fast pulley a¹⁵. The loose pulley a¹⁴, as shown in Fig. 2, is engaged by a belt a¹⁶, passed about a drum or pulley a¹⁷, on a shaft a¹⁸, connected by a belt 55 a¹⁹ with a pulley a²⁰ (see Fig. 1) on the crank-shaft a²¹ of the engine, the said crank-shaft being rotated through the connecting-rod a²² and piston-rod a²³ of an engine a²⁴, which may be of any usual or desired construction. The 60 shaft a¹⁸ is provided with a pulley b, connected by a belt b' (see Fig. 2) with a pulley b² on a shaft b³, having journals in suitable bearings b⁴. (See Fig. 3.) The shaft b² is provided on opposite sides of its center with a 65 right and left screw-thread or worm b⁵ b⁶, with which co-operate pallets or fingers b⁷ b⁸ on opposite ends of an armature-carrying bar b⁹,

pivoted, as at b¹⁰, to a casting or plate b¹², secured to or forming part of two sets of electromagnets b¹³ b¹⁴, each set of magnets, as herein shown, comprising two magnet-coils. 70

Each magnet-coil, as herein shown, has its front pole-piece extended beyond the face of the magnet, and the said pole-pieces have co-operating with them armatures b¹⁵ b¹⁶, secured to or forming part of the bar b⁹. The armatures b¹⁵ b¹⁶ are normally held away from their pole-pieces, as herein shown, by a spring b¹⁷, (see Fig. 3,) acting on the bar b⁹. The coils of the magnets b¹³ b¹⁴ are wound continuously, and one end of the wires of the said magnets are joined together and, as herein shown, connected to one pole of the battery B (see Fig. 1) by wire b¹⁸, the said wire, as shown, being connected to the negative pole of the battery B. The opposite end of each wire of the magnets is grounded or connected to the yokes or cross-bars b¹⁹ b²¹, connecting the cores of the said magnets. (See Figs. 1 and 5.) 80 85 90

The positive pole of the battery is connected by wire c, as shown in Fig. 1, to the shaft a⁸, and the circuit from the shaft a⁸ to the elevator-car may be traced through the metallic drum a⁴ and wire cable or rope a² to the bolt 95 c' on the elevator-car and from the bolt c' by wire c² to one portion or section c³ of the metallic rail, upon which run the metallic wheels c⁴ c⁵ of the car-door, as clearly shown in Fig. 7. 100

The electrical circuit through the rail referred to is broken, preferably, by a piece c⁶ of insulation interposed between the sections c³ and c^{3a} of the said rail, the circuit from the rail-section c³ across the insulation c⁶ being 105 traced through the wheel c⁴ to wheel c⁵ of the door by wire c⁷, connecting said wheels.

The rail-section c^{3a} has connected to it a wire c⁸, having its other end connected to a spring-arm c⁹, secured, as at c¹⁰, (see Fig. 6,) 110 to the bottom of the car and having its free end normally engaged by a spring-actuated pawl c¹² on a bar c¹³, carried by a lever c¹⁴, pivoted to the bottom of the car, the bar c¹³ being provided at its outer end with a roller 115 c¹⁵, for a purpose as will be described.

The spring-arm c⁹ constitutes one member of an automatically-operated switch, the co-operating member of which is herein shown as an arm c¹⁶, secured to the bottom of the 120 car, as by screws c¹⁷, which also secure to the car a second arm c¹⁸, extended substantially at right angles to the arm c¹⁶ and substantially in line with the pawl c¹², the end of the arm c¹⁸ being beveled or inclined to engage 125 the rounded or inclined part of the pawl c¹² to produce outward movement of the said pawl. The spring-arm c⁹ is normally in contact with the arm c¹⁶, and is disengaged therefrom substantially for an instant by the movement of 130 the pawl c¹², for a purpose as will be described. The arm c¹⁶ is connected by wire c²⁰ to the bolt c²¹, to which the wire cable a is secured. The wire cable a is connected by wire

c^{22} (see Fig. 1) to a spring-arm c^{23} , carried by the counterbalancing-weight a^3 , and making contact, as herein shown, with a metallic guide bar or rod c^{24} , to which one end of a wire c^{25} is secured, the said wire having its other end connected to the armature-carrying bar b^9 .

The elevator-car A is provided, as shown in Fig. 1, with two normally-open manual switches d d' , marked, respectively, "Up" and "Down," and shown as two contact-pieces secured to or forming part of a pointer or selecting-bar d^{50} , Fig. 8, fast on an arbor d^{51} , provided with a bevel-gear d^{52} , Fig. 9, in mesh with a bevel-gear d^{53} on a shaft d^{54} , extended below the car-floor. The arbor d^{51} has loose on it a preferably metallic bar d^{55} , provided with a handle of insulating material, the said bar forming a common contact member for the contact-pieces d d' . The bar d^{55} is connected by wire d^3 to the wire c^{20} , and the switch or contact-piece d is connected by wire d^4 to a contact-arm d^5 , secured to the car and in contact with a metallic bar or guide d^6 , which is herein shown as broken at its upper end near the top of the building and provided with a strip d^7 of insulating material, for a purpose to be described. The guide-bar d^6 below the strip d^7 is connected by wire d^8 to the yoke or cross-bar b^{21} of the magnet b^{14} , (marked in the drawings the "up" magnet.) The switch or contact member d' is connected by wire d^9 to a contact-arm d^{10} , carried by the car and normally in contact with a guide-bar d^{12} on the opposite side of the elevator shaft or well, as shown in Fig. 1. The guide-bar d^{12} is broken at its lower end or near the bottom of the elevator-well and electrically separated by the strip d^{13} of insulating material. The upper portion of the bar d^{12} is connected by wire d^{14} to the yoke or cross-bar b^{20} of the magnet b^{13} , (marked in Fig. 1 as the "down" magnet.) The selecting device or pointer d^{50} co-operates with a series of numbers indicating the floors or landings of the building in which the elevator is located. The shaft d^{54} , preferably below the car-floor, is provided with a segmental gear e^6 , (see Fig. 6,) in mesh with a rack-bar e^7 , movable in suitable guides e^8 , secured to the car-floor. The rack-bar e^7 has secured to or forming part of it a spring arm or extension e^9 , secured to a rod or bar e^{10} , provided at one end with a roller e^{12} , normally resting against the lever c^{14} , the bar e^{10} at its opposite end being provided, preferably, with a roller e^{13} , extended beyond the side of the car. The bar c^{13} , which is connected to the lever c^{14} , is preferably surrounded by a spiral spring e^4 , which acts against suitable guides secured to the car-floor and against a collar on the said bar to force the latter out into its normal position and bring the roller e^{15} on the end of the said bar outside of the car.

The side wall of the elevator in which the doors of the different landings are located is provided at each landing, near the doorway

thereof, with a projection or stud f , (marked 1, 2, 3, and 4 in Fig. 10,) with which co-operates the roller e^{13} , as will be described.

The spring-arm c^9 and its co-operating bar c^{16} constitute the automatically - operated switch carried by the elevator-car, as described, and the switches d and d' and also the car-door constitute manual switches carried by the car.

With the apparatus constructed as thus described the ascent and descent of the elevator-car may be controlled from within the elevator—as, for instance, let it be supposed that it is desired to ascend. The operator on the car closes the circuit of the up switch by moving the handle of the bar d^{55} toward the left, as shown in Figs. 1 and 8, thereby closing the circuit of the up magnet at the switch d , which circuit may be traced as follows: from the positive pole of the battery by wire c , shaft a^3 , drum a^4 , cable a^2 to the bolt c' on the car, and from the bolt c' by wire c^2 to the rail c^3 , thence by the wheel c^1 , wire c^7 , wheel c^8 to the rail c^{30} , thence by wire c^8 , spring-arm c^9 , arm c^{16} , wire c^{20} , thence by branch wire d^3 through the bar d^{55} , a contact member of the switch d , wire d^4 to contact-arm d^5 , thence by guide-bar d^6 , wire d^8 to the yoke b^{21} of the magnet b^{14} , through the coils of the said magnet to the negative pole of the battery by wire b^{18} . When the up magnet b^{14} becomes magnetized, the armature b^{16} , Fig. 3, is attracted, and the bar b^9 is turned on its pivot, so as to bring the pallet or finger b^7 into engagement with the worm b^5 . When the pallet b^7 on the armature - carrying bar b^9 is brought in contact with the worm b^5 , the said pallet is caused to travel or is moved toward the right or in the direction of arrow 21, Figs. 2 and 3. As the pallet b^7 is moved toward the right, it carries with it the casting b^{12} and the belt a^{16} , which is engaged by pins 25 on the upper plate of the casting b^{12} , the said plate having secured to or forming part it an arm 27, pivoted, as at 28, (see Fig. 2,) to a cross bar or frame 29. As the casting b^{12} is moved in the direction of arrow 21, the belt a^{16} is shipped from its loose pulley a^{14} to the fast pulley a^{15} , which is rotated in the direction indicated by arrow thereon in Fig. 2. As soon as the belt a^{16} is brought into engagement with the fast pulley a^{15} , the pulley a^{10} is rotated, and the belt a^9 thereon made to travel in direction of arrow 30, Fig. 1, thereby winding the drum a^4 in the direction of arrow 31 and hoisting the elevator. As soon as the armature b^{16} comes in contact with the pole-piece of the magnet b^{14} a circuit for the said magnet is completed through the bar b^9 , as will be described, so that as soon as the operator in the car has pressed the push-button or switch d to complete the circuit he may immediately remove the pressure or break the circuit at the switch d on the car. The circuit of the up magnet is now broken on the car, but yet remains completed through its armature, and this completed circuit may

be traced as follows: from the positive pole of the battery by wire c , shaft a^8 , drum a^4 , cable a^2 to the car, wire c^2 , rail c^3 , wheel c^4 , wire c^5 , wheel c^5 , rail c^{3a} , wire c^8 , spring-arm 5 c^9 , arm c^{16} , wire c^{20} to the bolt c^{21} , thence by cable a , wire c^{22} , and contact-arm c^{23} , guide-bar c^{24} , and wire c^{25} to the armature-carrying bar b^9 , through the armature b^{16} , core of the magnet b^{14} , then through the coils of the magnet and wire b^{18} to the negative pole of the battery.

The circuit of the up magnet just described will be maintained closed and the car will continue to travel upward until the said circuit is positively broken from the car.

The circuit may be broken by one of the projections f on the wall of the elevator-well, it acting on the roller e^{13} , so as to force the said roller and its bar outward, or in the direction of arrow 20, Fig. 6, and thus automatically remove the spring-arm c^9 from contact with the arm c^{16} , thereby breaking the said circuit at that point.

The operator on the car selects through the 25 pointer d^{50} which projection f shall break the circuit—as, for instance, if he desires to go to the third floor he turns his pointer or selecting device until it registers with the number 3 on the dial indicating the third 30 floor. As the pointer d^{50} is turned a bar d^{51} is also turned, and the shaft d^{51} is rotated through the gears $d^{52} d^{53}$, and the rack-bar e^7 , through the segmental gear e^6 , is moved along in its guides e^5 until the roller e^{13} stands or is 35 brought in line with the projection f marked 3, which projection, as has been stated, is so located with relation to the third landing that when the roller e^{13} meets the projection f marked 3 the door of the elevator-car will be 40 substantially opposite the door on the landing. When the roller e^{13} is acted upon by the projection f marked 3 and the bar e^{10} is moved in the direction of arrow 20, the said bar acts on the lever c^{14} and moves the said 45 lever and the bar e^{13} carried by it in the direction of arrow 20, thereby carrying the spring-arm c^9 away from its co-operating contact-arm c^{16} and breaking the circuit of the up magnet at that point, as described. As 50 the bar e^{13} is moved in the direction of arrow 20, the pawl c^{12} is moved outward by the inclined end of the arm c^{18} and is disengaged from the spring-arm c^9 , thus permitting the latter to fly back and again make electrical 55 connection with the arms c^{16} , closing the circuit of the up magnet at that point. As soon as the spring-arm c^9 , through the pawl c^{12} , is removed from contact with its co-operating contact member c^{16} , the circuit of the 60 up magnet is broken at that point, and the said magnet becomes demagnetized, thus permitting the spring b^{17} , Fig. 3, to center the armature-carrying bar b^9 and remove the pallet b^7 from engagement with the worm b^5 . 65 As soon as the pallet is moved from engagement with the worm b^5 the shipper-bar 27 is centered, as herein shown, by means of a

weight 32, connected by a cord 33 to the bar 27, as shown in dotted lines, Fig. 3, the said cord passing under a pulley 34 and over a 70 pulley 35. The elevator is now supposed to be stationary and opposite the third floor of the building, and if it is desired to descend the switch d^7 will be closed, thus magnetizing the down magnet b^{13} , the circuit being 75 traced as follows: from the positive pole of the battery by wire c , shaft a^8 , drum a^4 , cable a^2 , wire c^2 , rail c^3 , wheels $c^4 c^5$, rail c^{3a} , wire c^8 , through the automatic switch, wire c^{20} , branch wire d^3 , wire d^9 , contact-arm d^{10} , 80 guide-bar d^{12} , wire d^{14} to the yoke b^{20} of the magnet b^{13} , thence through the coils of the said magnet to the negative pole by wire b^{18} . As soon as the circuit of the down magnet is closed at the switch d^7 it attracts its armature b^{15} , thereby engaging the pallet b^8 with the worm b^6 , which moves the shipper 85 27 in the direction opposite to that indicated by arrow 21, Fig. 2, and brings the belt a^{16} into engagement with the fast pulley a^{13} on the 90 shaft a^7 , thereby producing rotation of the drum a^4 , through the belt a^5 , in the direction of arrow 40, and permitting the car to descend.

If it is desired to stop the car at any floor 95 or landing below the third, the bar d^{55} will be moved until the pointer d^{50} registers with the number indicating such floor, and the roller e^{13} will be thus placed in position to be acted upon by the projection f at the selected floor, 100 the said projection acting on the said roller to break the circuit of the down magnet at the automatically-operated switch c^9 carried by the car.

In order that the travel of the elevator may 105 be controlled from each landing of the building, I have provided at each landing a switch k , provided with two contact-terminals $k' k^2$, which co-operate with contact-terminals $k^3 k^4$. The contact-terminal k^4 has connected in circuit with it an electro-magnet k^5 , which is connected by wire k^6 with the wire b^{18} , leading to the negative pole of the battery. The contact-terminal k^2 is connected by wire k^7 with a wire k^8 , having one end connected to a 110 guide bar or rod k^9 , with which co-operates a contact member k^{10} , joined by wire k^{12} to the cable a' , which is connected by a wire k^{13} to one terminal of a bell k^{14} of any ordinary construction, the other terminal of the said 115 bell being connected by wire k^{15} to the wire c^2 . The contact-terminal k' is connected by wire k^{20} to the wire c^{25} , and the contact-terminal k^3 , co-operating with the terminal k' , is connected, as herein shown, by wire k^{21} to a 120 cam-switch (herein shown as a pivoted rocker k^{22}) located in a suitable case k^{23} , Figs. 17 and 18, in which the magnet k^5 is placed. The rocker k^{22} is preferably provided with two 125 spring-arms $k^{24} k^{25}$, which co-operate with pins 130 or studs $k^{26} k^{27}$, Fig. 18, connected, respectively, by wires $k^{28} k^{29}$, Fig. 1, with the wires d^{14} and d^8 . The rocker k^{22} co-operates with a projection on a lever k^{30} , Fig. 18, pivoted as

at k^{31} , and normally kept in engagement with the said rocker by a spring k^{32} . The lower end of the lever k^{30} engages a notch in a lever k^{35} , pivoted as at k^{36} , (see Fig. 18,) and normally kept in elevated position by a spring k^{37} . The lever k^{35} constitutes a locking device for a cam-lever k^{40} , (see Fig. 17,) pivoted as at k^{41} , and having an arm k^{42} , constituting the armature for the magnet k^5 . The cam-lever k^{40} is provided with two oppositely-inclined faces 36 37, with which co-operates the roller c^{15} , Fig. 6, on the bar c^{13} , carried by the elevator-car. The rocker k^{22} is acted upon by a fixed roller or projection k^{44} , (see Fig. 6,) which is carried by the car.

In order that the operation of the device on the landing may be readily understood, let it be supposed that the switch k on the third landing (marked L^3 in Figs. 1 and 10) has been closed, and that the elevator at such time is in the position indicated in Fig. 1. As soon as the switch k is closed the circuit of the magnet k^5 is closed, and the said magnet attracts its armature k^{42} and moves the lever k^{40} from its full-line position in Fig. 17 out into its dotted-line position. As soon as the switch k is closed the bell k^{14} , carried by the car, is rung, its circuit being closed, which circuit may be traced as follows: from the positive pole of the battery by wire c , shaft a^8 , drum a^4 , cable a^2 , wire c^2 , through the bell, wire k^{13} , cable a' , wire k^{12} , contact member k^{10} , guide-bar k^9 , wires k^8 , and k^7 to contact-terminal k^2 , through the magnet k^5 , and thence by wire k^6 and wire b^{18} to the negative pole of the battery. As soon as the switch k is closed the circuit of the up magnet is closed at the said switch, and the elevator is made to travel upward, as above described, the circuit for the switch k through the said magnet being traced as follows: from the positive pole of the battery by wire c , shaft a^8 , drum a^4 , cable a^2 , wire c^2 , through the door, as described, wire c^8 , automatic switch, wire c^{20} , cable a , wire c^{22} , contact member c^{23} , guide-bar c^{24} , wire c^{25} , wire k^{20} , contact-terminals k' k^3 , wire k^{21} , rocker k^{22} , spring-arm k^{25} , pin k^{27} , wire k^{29} , and wire d^8 to the yoke b^{21} of the up magnet, thence through the magnet to the negative pole of the battery by wire b^{18} . As soon as the elevator has reached the landing b^3 and the door of the elevator is substantially opposite the door on the landing the roller c^{15} rides up the inclined side 36 and breaks the circuit of the up magnet at the automatically-operated switch, as above described, thereby stopping the car. At substantially the same time the fixed roller k^{44} acts on the rocker k^{22} and turns the said rocker on its pivot, thereby removing the spring-arm k^{35} from the pin k^{27} and breaking the circuit of the up magnet at that point also, and at the same time bringing the spring-arm k^{34} into engagement with the pin k^{26} , Fig. 18, closing the circuit of the down magnet at the said pin and arm. As soon as the rocker is turned on its pivot by the roller k^{44} the lever k^{35} , which has previ-

ously engaged a projection k^{50} (see Fig. 17) on the cam k^{40} and held the same securely locked in its outer or dotted-line position, is moved down by the lever k^{30} , riding up the inclined notch k^{51} in the lever k^{35} , thus moving the end of the lever k^{35} down out of the path of movement of the projection k^{50} and permitting the lever k^{40} to be moved into its normal or full-line position. With the rocker k^{22} moved into its dotted-line position, and with the spring-arm k^{34} in contact with the stud k^{26} , the circuit of the down magnet alone is closed, and the said circuit is closed at all the rockers below the third floor, so that if the switch k at either the first or second floor should be closed the elevator will be moved downward.

As shown in Fig. 1, only the rocker k on the first floor is shown in position to close the down magnet b^{13} , so that if the switch k on the first floor (marked L') should be closed the down magnet will be energized and the elevator brought to the first floor.

The circuit of the down magnet through the switch k on the first floor may be traced as follows: from the positive pole of the battery by wire c , shaft a^8 , drum a^4 , cable a^2 , wire c^2 , through the car-door, as described, wire c^8 , automatic switch, wire c^{20} , cable a , wire c^{22} , contact-arm c^{23} , guide-bar c^{24} , wire c^{25} , wire k^{20} , terminals k' k^3 , wire k^{21} , rocker k^{22} , spring k^{24} , pin k^{26} , wire k^{28} , and wire d^{14} to the yoke b^{20} of the magnet, thence through the magnet b^{13} to the negative pole of the battery. As soon as the switch k on the first floor is closed and the magnet b^{13} energized the armature b^{15} , Fig. 3, of the said magnet is attracted and the circuit of the magnet b^{13} is maintained closed, as above described. The roller k^{44} on the downward movement of the elevator acts on the rocker k^{22} at the third and second floors and moves them from the position indicated by dotted line in Fig. 18 to their full-line position, closing the circuit of the up magnet at the spring-arm k^{25} and pin k^{27} .

As soon as the elevator in its downward passage has reached substantially the bottom of the elevator-well, and the car-door is substantially opposite the door at the first landing, the circuit of the down magnet is broken, as herein shown, by the insulated strip d^{18} , and the down magnet b^{13} is demagnetized and the belt a^{16} placed in contact with the loose pulley a^{14} . The circuit of the up magnet at the top of the elevator-well may be broken in a similar manner by the insulated strip d^7 in the guide-bar d^6 when the elevator is at the top of the well.

From the foregoing description it will be seen that by means of my invention the elevator-car may be started and stopped not only on the car itself, but also from any desired point or station in the travel of the car—as, for instance, at any desired landing. Furthermore, it will be noticed that the car automatically operates a switch at the landing, which switch is shown in the present instance as a rocker, so that the said car in its travel

by a landing in either direction leaves the said switch in such position as to close the circuit at the said switch of the magnet necessary to be operated to bring the said car to the desired landing or station. This is especially advantageous in apartment-hotels, as the elevator can be run without the employment of an attendant in the car.

I have thus far described my invention as employed to control the movement of an elevator-car; but I do not desire to limit my invention to this use, as it may be employed to control the movement of any form of car or carriage or other movable body—such, for instance, as shown in Fig. 19, wherein is represented a car-truck having its axles m m' mounted on wheels m^2 , running on a track m^3 . On opposite sides of the track are located conductors m^4 m^5 , the conductor m^4 , as herein shown, being connected to one pole (as the positive pole) of the battery by wire m^6 , the other conductor m^5 being connected to the negative pole of the battery by wire m^7 , which is shown as broken and connected to rail-sections m^8 m^9 , on which run wheels m^{10} m^{12} of a door, the said wheels being joined by wire m^{13} in a similar manner to the rail-sections on the elevator-car. The axle m is electrically divided, as by insulation m^{14} , into two parts, (marked 7071,) and the axle m' is electrically divided in a similar manner into two parts 72 73. The car is driven by a motor m^{16} , herein shown as a compound-wound electric motor, one wire m^{17} being connected to one coil 81 of a magnet m^{18} , and the other wire m^{19} being connected to one coil 80 of the magnet m^{20} . The magnets m^{18} m^{20} , as shown, have a common armature m^{21} . The motor has its armature-shaft provided with the usual commutator and brushes m^{22} m^{23} , the brush m^{22} being connected in circuit with the field-wires m^{17} m^{19} of the motor, and the brush m^{23} being connected by wire m^{24} with a current-collector m^{25} , co-operating with the conductor m^4 . The armature-shaft, as shown, is provided with a pinion m^{26} , in mesh with a gear m^{27} on the axle m' . The axle m has mounted on it a pinion n , connected, as shown, by intermediate gears to a large gear n' , constituting a brake-gear, with which co-operates a pawl n^2 , forming the armature of a magnet n^3 , having one of its wires n^4 connected to a current-collector n^5 , co-operating with the conductor m^5 , the other wire n^6 of the said magnet being connected to member n^7 of an automatically-operated switch, similar to the automatically-operated switch on the elevator-car, the other member n^8 of the said switch being connected by wire n^9 to one coil, as 79, of the magnet m^{18} , and the wire n^9 is connected to the coil, as 76, of the magnet m^{20} by branch wire 77. The wire n^9 is connected by wire n^{10} to a switch provided with two contact-terminals n^{12} n^{13} , co-operating with contact-terminals n^{14} n^{15} , the terminal n^{14} being connected by wire n^{16} to the part 72 of the axle m' , and the terminal n^{15} to the part 73 of the said axle by wire

n^{17} . The wire n^{16} is connected by wire n^{18} to the coil 80 of the magnet m^{20} , and the wire n^{17} is connected by wire n^{20} to the coil 81 of the magnet m^{18} .

For purpose of illustration let it be supposed that when the magnet m^{18} is energized the motor will propel the car forward or in the direction of arrow 100, and that when the magnet m^{20} is energized the motor will move the car in a direction opposite to that indicated by the arrow 100. Let it be supposed that the operator desires the car should move forward or in the direction of arrow 100. In this case the switch on the car is operated to bring the terminal n^{13} in contact with the terminal n^{15} , thereby completing the circuit of the coil 81 of the magnet m^{18} , which circuit may be traced as follows, viz: from the positive pole of the battery by wire m^6 , conductor m^4 , collector m^{25} , wire m^{24} to brush m^{23} , through the armature, thence by brush m^{22} , through the field-magnet wire m^{17} through the coil 81, thence by wires n^{20} n^{17} to the terminals n^{15} n^{13} , thence by wire n^{10} to the automatic switch n^8 n^7 , thence by wire n^6 , through the magnet n^3 , wire n^4 , to collector n^5 , through the conductor m^5 , wire m^7 , rail-section m^8 , wheels m^{10} , wire m^{13} , wheel m^{12} , rail-section m^9 to the negative pole of the battery.

As shown in Fig. 19, both of the doors o o' are closed, and the circuit of the motor is complete and the said motor moves the car forward.

As soon as the operator in the car has completed the circuit of the magnet-coil 81, as described, he may break the said circuit by withdrawing the terminal n^{13} from the terminal n^{15} ; but the circuit of the motor is still maintained closed through the armature and the coil 79 of the magnet m^{18} , the said armature being brought in contact with the core of the coil 79, to which the wire n^9 is connected, or, as it is technically known, is "grounded."

The circuit may now be traced as follows, viz: from positive pole of the battery by wire m^6 , conductor m^4 , collector m^{25} , wire m^{24} , through the armature-wire m^{17} , contact-stud 90, to which the said wire is connected and with which the armature is brought in contact, through the armature m^{21} , coil 79, wire n^9 , switch n^8 n^7 , wire n^6 , magnet n^3 , wire n^4 to collector n^5 , through the conductor m^5 , wire m^7 , and doors o o' to the negative pole of the battery. The car continues to travel forward until a projection carried by the car and indicated by dotted lines 50, and which may be similar to the projection e^{13} on the elevator-car, as shown in Fig. 6, is struck by a stud or projection o^2 , located, as shown, between the rails of the track, the said stud acting on the projection on the car to open the automatic switch, and thus break the circuit of the magnet-coil 79, and thereby stop the car, the circuit of the motor and magnet n^3 being thus broken. As soon as the circuit is thus broken the armature n^2 is

moved away from the pole of the magnet n^3 either by a spring (not shown) or by gravity, or in any other usual manner, and the pawl n^2 on the said armature is brought into engagement with the gear-wheel n' , thus stopping rotation of the axle m .

If it is desired to make the car travel in the direction opposite to that indicated by arrow 100, the terminal n^{12} will be brought in contact with the terminal n^{14} and the circuit of the coil 80 of the magnet m^{20} closed, thereby moving the armature m^{21} into contact with the core of the coil 76 of the magnet m^{20} , and also in contact with the stud 91, to which the wire m^{19} is connected, the circuit of the motor being maintained closed, through the coil 76, after the circuit of the coil 80 is broken on the car at the terminals n^{12} n^{14} .

The circuit of the coil 80 may be traced as follows, viz: from the positive pole of the battery by wire m^6 , conductor m^4 , collector m^{25} , wire m^{24} , through the armature to brush m^{22} , thence through field-magnet wires m^{19} , coil 80, wire n^{18} , terminals n^{14} n^{12} , wire n^{10} , through automatic switch, magnet n^3 , wire n^4 , collector n^5 , conductor m^3 , to the pole of the battery, as above described.

The circuit of the coil 76 may be traced as follows, viz: from the positive pole by wire m^6 , conductor m^4 , collector m^{25} , wire m^{24} , through the armature, wire m^{19} , stud 91, armature m^{21} , coil 76, wire n^9 , automatic switch, magnet n^3 to negative pole of the battery, as described.

As thus far described the movement of the car is controlled from the car; but it may also be controlled from different points or stations along the track, which stations may be supposed to be located at the doors o o' .

Each station will be provided with a switch, preferably a push-button having terminals p p' , co-operating with terminals p^2 p^3 , and at each station will be located a device substantially such as is located at each landing of the elevator-well, which device will preferably consist of the magnet k^5 , controlling the cam k^{40} , having attached to it the armature k^{42} , and by which the car is automatically stopped at the station at which the magnet k^5 is energized, the said armature and cam being not shown in Fig. 19. One terminal of the switch, as p^3 , will be connected to the rocker k^{22} , co-operating with the terminals k^{26} k^{27} , by which the circuit of that magnet on the car necessary to be energized to bring the car to the said station is placed in proper condition, so that the said circuit will be completed when the push-button or switch at the station is operated.

In practice the magnet k^5 and the rocker k^{22} will preferably be contained in a box similar to that shown in Figs. 17 and 18, and will be located between the tracks m^3 , so as to operate upon the projection 50 on the under side of the car-brake and the automatic switch, while the rocker k^{22} is operated upon by another projection 60 on the under side of

the car, as indicated by dotted lines, Fig. 19, which projection is similar to the projection k^{44} on the elevator-car.

70

At each station a bell p^5 is preferably located, the bell at one station having one wire, as p^6 , connected to one of the wheels, as m^{10} , of the door, and its other wire connected to a contact piece or arm p^7 , extended from the door and adapted to co-operate with a similar arm p^8 , connected by wire p^9 , as shown, to the terminal p of the push-bottom. The wire p^6 of the bell at the station o' is connected to the wheel m^{12} of the door. The positive pole of the battery has connected to it a branch wire p^{80} , (shown by dotted lines in Fig. 19,) and to which is connected the terminals p^2 of the switches at the different stations. The magnet k^5 , which is indicated in the diagram, Fig. 19, by a circle, has one wire connected to the terminal p' , and the other wire p^{10} of the magnet at the station o' is connected to the wire m^7 , while the wire p^{10} of the magnet k^5 , located at the station o , is connected, as shown, to the wire p^{12} , joining the rail-sections m^8 m^9 of adjacent doors. The terminals p of the switches at adjacent stations are connected by wire p^{19} . When the door of a section or station is open, the circuit of the bell at that station will be completed when the switch or push-button at another station is operated. For instance, let it be supposed that the door o' of the station is open and that the operator at the station o wants the car. In this instance the operator closes the switch or push-button p , which completes the circuit of the bell p^5 at the station o' , which circuit may be traced as follows: from the positive pole of the battery by wire p^{80} to terminal p^2 of the switch or push-button at the station o , thence by terminal p , wires p^{19} p^9 to contact-arm p^8 , through the bell-wire p^6 , rail-section m^9 , wire p^{12} , through the door o and negative wire m^7 connected thereto to the battery. The ringing of the bell at the station o' notifies the operator or attendant at that station that the car is wanted at some other station, and gives notice to him that his door must be closed in order to complete the circuit of the magnets which control the movement of the car.

85

The operation of the car as shown in Fig. 19 is identical with the operation of the elevator-car shown in Fig. 1, and the manner of controlling it both from the car itself and from the different stations is identical.

90

In Fig. 1 I have shown and described the electro-magnets as controlling the operation of a belt-shifter by which the elevator-car is raised; but I do not desire to limit my invention to this particular class of mechanism for actuating the elevator, as other forms may be used—such, for instance, as shown in Fig. 20, wherein the electro-magnets control an electromotor s , having in circuit with it a resistance s' , by which the excessive current on starting up of the motor—namely, at the starting of the elevator-car—is prevented from burning out or otherwise injuring the motor,

100

105

110

115

120

125

130

the movement of the resistance-lever s^2 being controlled by a solenoid s^3 , having connected to its core a piston of a dash-pot s^4 , which latter also obviates the starting of the car with 5 a jerk.

As shown in Fig. 21, the electro-magnets $b^{13} b^{14}$ are connected to and control the circuits of solenoids $s^5 s^6$, having, as shown, a common core s^7 , which, as herein shown, is connected 10 to a valve s^8 , controlling the ports of a cylinder in which is reciprocated a piston s^9 , having its piston-rod s^{10} connected in suitable manner to the hoisting mechanism or to a main valve. So, also, the magnets $b^{13} b^{14}$ may 15 be connected to a compound-wound solenoid s^{12} , Fig. 22, having its wires $s^{13} s^{14}$ connected to a compound-wound motor s^{15} , having its armature-shaft s^{16} connected by belt s^{17} to a pulley on a shaft s^{18} , provided with a worm 20 s^{19} , somewhat similar to the worm shown in Fig. 3. The solenoid s^{12} has a core s^{20} , having an arm s^{21} , to which is secured a belt-shipper s^{23} , provided with teeth or serrations s^{22} , which are brought into engagement with the worm 25 s^{19} when the solenoid s^{12} is energized, which occurs when the circuit of either of the magnets $b^{13} b^{14}$ is closed.

When one magnet, as b^{13} , is energized, it attracts its armature, closes the circuit of one 30 coil of the solenoid s^{12} , which revolves the armature of the motor in one direction, thereby revolving the shaft s^{18} in one direction, and through the teeth s^{22} on the shipper s^{23} moves the belt from the loose pulley s^{24} to a fast 35 pulley, as s^{25} , producing travel of the elevator in one direction, and when the magnet b^{14} is energized the circuit of the coil of wire s^{14} of the solenoid and motor is completed, and the shaft s^{18} is revolved in the opposite direction 40 and the belt shifted to the fast pulley s^{27} , causing the travel of the elevator in the opposite direction.

Instead of the particular form of selecting device shown in Figs. 1, 8, and 9, I may employ any other form of selecting device—such, for instance, as shown in Figs. 14 and 15, wherein the pointer d^{50} is mounted on the arbor d^{51} , extended through a disk or dial e' , provided with numbers indicating the different stations. In this instance two push-buttons of ordinary construction are employed, 45 as the switches $d d'$.

I have herein shown the magnetic device as consisting of an electro-magnet having two 50 cores wound continuously; but instead thereof it is evident one core having a compound or double winding may be used.

I claim—

1. The combination, with a car or carriage 55 and a motor mechanism to cause the said car or carriage to travel, of a magnetic device operatively connected to the car or carriage to control the operation of the motor mechanism from the car, a manual switch, and an independent automatic switch carried by the 60 car in circuit with the magnetic device, and a cam or projection in the path of movement

of the car to operate the said automatic switch and stop the car, substantially as described.

2. The combination, with a car or carriage 65 and a motor mechanism to cause the said car or carriage to travel, of a magnetic device to control the operation of the motor mechanism, terminals at one or more points or stations in circuit with the said magnetic device, an automatic switch carried by the car or carriage, and a cam or projection in the path of movement of the car to operate the said automatic switch and stop the car, substantially as described. 70

3. The combination, with a car or carriage and a motor mechanism to cause the said car or carriage to travel, of a normally-closed automatically-operated switch carried by the car, an electro-magnet having its coil in circuit with said switch, normally-open terminals carried by the car in circuit with the coil of the said electro-magnet, an armature for said magnet in circuit with the said automatic switch and adapted to maintain closed 85 the circuit of the electro-magnet after it has been broken at one of the said terminals, and a cam or projection in the path of movement of the said automatic switch to break the circuit of the magnet, substantially as described. 90

4. The combination, with a car or carriage and a motor mechanism to cause the said car or carriage to travel, of a normally-closed automatically-operated switch carried by the car, an electro-magnet having its coil in circuit with said switch, a manual switch in circuit with the said electro-magnet, and a cam or projection in the path of movement of the 100 said automatic switch, to operate substantially as described. 105

5. The combination, with a car or carriage and a motor mechanism to cause the said car or carriage to travel, of a magnetic device to control the operation of the motor mechanism, terminals at one or more points or stations in circuit with the said magnetic device, an automatic switch carried by the car or carriage, and a cam or projection in the path of movement of the car to operate the said automatic switch and stop the car, a switch in the path of movement of the car in circuit with the magnetic device, and a projection on the car to actuate the switch, substantially as described. 110

6. The combination, with a car or carriage and a motor mechanism to cause the said car or carriage to travel, of a magnetic device operatively connected to the car or carriage to control the operation of the motor mechanism from the car, a manual switch, and an automatic switch carried by the car in circuit 120 with the magnetic device, and a series of projections in the path of movement of the car out of line with each other, and a selecting device operated on the car to cause the automatic switch to be broken by any of the said 125 projections, substantially as described.

7. The combination, with a car or carriage and a motor mechanism to cause the said car or carriage to travel, of a magnetic device to

- control the operation of the motor mechanism, terminals at one or more points or stations in circuit with the said magnetic device, an automatic switch carried by the car or carriage, and a cam or projection in the path of movement of the car to operate the said automatic switch and stop the car, and a magnet located at the point or station to operate said projection, substantially as described.
8. The combination, with a car or carriage and a motor mechanism to cause the said car or carriage to travel, of a normally-closed automatically-operated switch carried by the car, an electro-magnet having its coil in circuit with said switch, a switch in the path of movement of the said car connected in circuit with the said electro-magnet coil, a projection on the car to operate said switch, a cam or projection, and a magnet to place said cam or projection in position to open the automatic switch and stop the car, substantially as described.
9. The combination, with a car or carriage and a motor mechanism to cause the said car or carriage to travel, of a magnetic device to control the operation of the motor mechanism, terminals at one or more points or stations in circuit with the said magnetic device, an automatic switch carried by the car or carriage, and a movable cam or projection in the path of movement of the car to operate the said automatic switch and stop the car, and a locking device to lock said cam or projection in its operative position, substantially as described.
10. The combination, with a car or carriage and a motor mechanism to cause the said car or carriage to travel, of a magnetic device to control the operation of the motor mechanism, terminals at one or more points or stations in circuit with the said magnetic device, an automatic switch carried by the car or carriage, and a movable cam or projection in the path of movement of the car to operate the said automatic switch and stop the car, and a locking device to lock said cam or projection in its operative position, substantially as described.
11. The combination, with a car or carriage and a motor mechanism to cause the said car or carriage to travel, of a magnetic device to control the operation of the motor mechanism, terminals at one or more points or stations in circuit with the said magnetic device, an automatic switch carried by the car or carriage, and a cam or projection in the path of movement of the car to operate the said automatic switch and stop the car, and a locking device to lock said cam or projection in its operative position, and a switch to release or unlock said cam or projection, substantially as described.
12. The combination, with a car or carriage and a motor mechanism to cause the said car or carriage to travel, of a magnetic device operatively connected to the car or carriage to control the operation of the motor mechanism from the car, a selecting device, and a normally-open switch co-operating with said selecting device and adapted to be closed by the movement of the said selecting device, an automatic switch carried by the car in circuit with the magnetic device, and a cam or projection in the path of movement of the car to operate the said automatic switch and stop the car, substantially as described.
13. The combination, with a car or carriage and a motor mechanism to cause the said car or carriage to travel, of a magnetic device to control the operation of the motor mechanism, terminals at one or more points or stations in circuit with the said magnetic device, and a bell on the car or carriage in circuit with the said terminals, an automatic switch carried by the car or carriage, and a cam or projection in the path of movement of the car to operate the said automatic switch and stop the car, substantially as described.
14. The combination, with a car or carriage provided with a door and a motor mechanism to cause the said car or carriage to travel, of a magnetic device operatively connected to the car or carriage and in circuit with the car-door to control the operation of the motor mechanism from the car, a manual switch on the car, and an automatic switch carried by the car in circuit with the magnetic device, and a cam or projection in the path of movement of the car to operate the said automatic switch and stop the car, the said door when opened breaking the circuit of the magnetic device to thereby render the car inoperative, substantially as described.

In testimony whereof I have signed my name to this specification in the presence of two subscribing witnesses.
